UNITED STATES PATENT OFFICE.

CARL A. JOHANNESEN, OF BROOKLYN, NEW YORK.

PROJECTILE.

1,242,944.

Specification of Letters Patent. Patented Oct. 16, 1917.

Application filed February 12, 1916. Serial No. 77,988.

To all whom it may concern:

Be it known that I, CARL A. JOHANNESEN, a subject of the King of Norway, residing at Brooklyn, in the county of Kings and State 5 of New York, have invented certain new and useful Improvements in Projectiles, of which the following is a specification.

My invention relates to ammunition and explosive devices, and more particularly to 10 an improved form of projectile for use in long range guns.

The primary object of my invention is to provide a projectile which affords a longer range and is of a greater power than the 15 projectiles now in common use and to construct such a projectile in a simple and cheap manner.

Another object of my invention is to provide a projectile which when fired from a 20 gun and before striking receives an additional impulse whereby to increase the strength of the blow or to lengthen the range.

With the above and other objects in view 25 my invention resides preferably in the construction, combination and arrangement of parts as hereinafter set forth in the specification and illustrated in the accompanying drawings, in which,

30 Figure 1 is a longitudinal sectional view of a projectile embodying the improvements of my invention.

Fig. 2 is a longitudinal sectional view 35 of the fighting head or explosive bullet.

Fig. 3 is a similar view of the shell having the fighting head removed.

Fig. 4 is a transverse sectional view taken 40 on the line 4-4 of Fig. 1, looking in the direction of the arrow, and

Fig. 5 is a front end elevational view of the shell.

Similar reference characters designate 45 similar parts throughout the various views of the drawings.

In the drawings, I have illustrated my improved projectile as preferably embodying a main casing or shell 1 open at one end and provided with a plurality of tortuous 50 grooves 2 on its inner peripheral face. The rear end of the shell is closed, as at 3, said closing end wall being provided with an opening 4 for a purpose which will hereinafter appear.

The fighting head or bullet includes a 55 casing or shell 5 substantially cylindrical in cross section and having a plurality of tor-

tuous tongues 6 on its outer peripheral face for engagement in the grooves 2 formed in the shell 1. The forward end of the shell 5 is enlarged and tapered to provide a penetrating head 7, said enlarged striking head having a shoulder 8 at its base which limits the movement of the bullet 5 into the main shell 1. The shell or bullet 5 is of a length which when inserted into the shell 1 will 60 afford a charge receiving chamber 9 in the rear thereof, said chamber being filled with an explosive charge 10 of any desired composition. A time fuse 11 leads to said chamber and is adapted to be ignited when the projectile is initially started on its flight. The bullet or shell 5 is filled with an explosive composition 12 which is adapted to be exploded when the head 7 strikes an object and the firing mechanism may employ the usual 65 detonating cap and mechanism therefor. This mechanism is indicated generally by the numeral 13. The front end of the shell 1 may be beveled, as indicated at 14, so that when the bullet and shell are assembled the 70 device presents an outward appearance 75 practically identical with that of the usual form of projectile.

In use, the projectile is placed in the breech of a gun and the usual charge of 80 smokeless powder inserted behind the same. The breech of the gun is closed in the usual manner and the powder is exploded causing the shell having the bullet 5 to be launched on its flight. In the initial discharge of the 85 gun the fuse 11 is lighted and when the fuse burns into the explosive composition 10 the latter will be exploded sending the bullet 5 farther than the original discharge. The grooves 2 and the tongues 6 must be formed 90 so that when the bullet is discharged from the shell 1 a twisting motion will be given to said bullet and of course these grooves and tongues must be oppositely arranged to the initial twisting motion given by the gun. 100 Attention is called to the fact that the charge 10 of explosive material must be of such strength as will not overcome the momentum of the shell 1 but will utilize the shell in its forward flight as a gun. It is of 105 course to be understood that the proportion of charges to be used as well as the timing of the fuse 11 may be developed when using the device in actual practice.

From the above description taken in connection with the accompanying drawings it is thought that a clear and comprehensive 110

understanding of the construction, operation and advantages of my invention may be readily gathered, and while I have shown and described the same as embodying a specific structure I desire that it be understood that I may make such changes therein which do not depart from the spirit and scope of the invention as claimed.

I claim:

10 In a projectile of the class described, a casing open at one end and closed at the other and provided with a plurality of oppositely disposed spiral grooves on its inner peripheral face, said grooves extending from said open end inwardly, a time fuse extending into said casing through the closed end thereof, a shell mounted in said casing and including a body portion having a solid cone-shaped head with a laterally extending shoulder at its base projecting beyond said body portion, said shell also having a plurality of oppositely disposed spiral

ribs extending from said shoulder toward its opposite end and positioned to engage the grooves of said casing, said shell having 25 its body portion snugly fitting within the casing with the shoulder at the base of its head abutting the open end of the casing, said shell body being of less length than said casing to provide an explosive chamber at 30 the rear of the shell when the parts are assembled, an explosive charge in said chamber, an explosive charge in the shell, a detonating cap in said shell, and a firing rod extending through the apex of said shell 35 head and adapted to coöperate with said cap to ignite the charge within the shell.

In testimony whereof I affix my signature in presence of two witnesses:

CARL A. JOHANNESEN.

Witnesses:

JACOB ANDREASEN,
NILS JOHANNESEN.
